Primary Examiner — Leanne Was-Englehart*(74) Attorney, Agent, or Firm* — Law Office of Jeff Williams PLLC; J. Oliver Williams(57) **CLAIM**

The ornamental design for a solar screen with plantation shutter, as shown and described.

DESCRIPTION

FIG. 1 is an oblique view of a solar screen with plantation shutter according to the present application.

FIG. 2 is a front view of the solar screen with plantation shutter of FIG. 1.

FIG. 3 is a rear view of the solar screen with plantation shutter of FIG. 1.

FIG. 4 is a right view of the solar screen with plantation shutter of FIG. 1.

FIG. 5 is a left view of the solar screen with plantation shutter of FIG. 1.

FIG. 6 is a top view of the solar screen with plantation shutter of FIG. 1; and,

FIG. 7 is a bottom view of the solar screen with plantation shutter of FIG. 1.

The broken lines are included for the purpose of illustrating environmental structure and form no part of the claimed design.

1 Claim, 5 Drawing Sheets(56)
